Application August 17, 1944, Serial No. 549,877

10 Claims. (Cl. 103—41)

1

This invention relates to pumping means and more particularly to apparatus adapted for pumping liquids, such as liquid fuel into the cylinders of internal combustion engines.

One of the objects of the present invention is to provide a novel pump for pumping liquids wherein leakage of the liquid through the clearance space between the plunger and cylinder of the pump is reduced to a minimum.

Another object of the invention is to provide a pump of the above character wherein the liquid which leaks along the plunger is returned directly to the supply line of the pump or other region of low pressure in a novel manner.

Still another object is to provide a high pressure fuel injection pump, or the like, which embodies novel means for preventing leakage during the pressure stroke of the plunger thereof, said means being particularly applicable to small compact pumps.

A further object is to provide novel means of the above character which may be readily incorporated into pumps which are currently being manufactured in large quantities.

Still another object is to provide a novelly constructed fuel pump wherein fuel is conserved and more accurate metering is assured.

The above and further objects and novel features of the invention will more fully appear from the following detailed description when the same is read in connection with the accompanying drawings. It is to be expressly understood, however, that the drawings are for the purpose of illustration only and are not intended as a definition of the limits of the invention, reference for this latter purpose being had primarily to the appended claims.

In the drawings, wherein like reference characters refer to like parts throughout the several views,

Fig. 1 is a side elevation partly in section showing one form of fuel injection pump embodying the present invention, the section being taken substantially on line 1—1 of Fig. 2;

Fig. 2 is a transverse sectional view taken substantially on line 2—2 of Fig. 1;

Fig. 3 is a detail sectional view with parts broken away and with parts shown in full, the section being taken substantially on line 3—3 of Fig. 2; and,

Fig. 4 is a diagrammatic view showing the superposed developed circumferences of the pump cylinder and plunger when the latter is in full load position and just closing the intake port on its pressure stroke.

A single embodiment of the invention is illustrated in the drawings, by way of example, in the form of a fuel pump for injecting solid liquid fuel into the cylinders of internal combustion engines. The particular pump assembly shown

2

comprises a tubular casing 5 having laterally projecting ears 6 by means of which the same may be secured to an engine cylinder or other support, not shown. Mounted in the casing 5 intermediate the ends thereof is a pump cylinder 7 which is supported on an internal shoulder 8 within the casing. Cylinder 7 may be held against rotary movement in casing 5 by any suitable means well known in the art, such as by means of a screw (not shown) which threadedly engages casing 5 and projects into any axially extending groove in the outer wall of the cylinder. An inlet port 11 and a by-pass port 12 are provided in the wall of cylinder 7 near the upper end thereof, as viewed in the drawings, for directing the flow of fuel to and from the cylinder in a manner to more fully appear hereafter.

Slidably extending into cylinder 7 from the lower end thereof is a pump plunger or piston 13 which also functions as a slide valve for controlling the flow of fuel through ports 11 and 12. For a purpose that will more fully appear from the description of the operation of the pump which follows, the plunger 13 is provided with an axially extending passage 14 and a radial passage 15 which continuously connect the upper end or pressure chamber 17 of cylinder 7 to a helical groove 16 cut into the surface of plunger 13. Groove 16 is adapted to cooperate with port 12 when the plunger moves upwardly and constitutes a metering, bypass or cut-off groove which determines the effective pumping stroke of the plunger. If desired, a groove or recess 18a may be provided in the surface of plunger 13 opposite groove 16 in communication with passage 15 to thereby balance or partially balance the fluid pressure acting on opposite sides of the plunger during the pressure stroke thereof.

Any suitable means may be provided for angularly adjusting piston 13 for the purpose of changing the relation between metering groove 16 and cut-off or by-pass port 12 to thereby vary the effective pumping stroke of the piston in a manner well understood in the art. In the illustrated embodiment, the piston adjusting or control means comprises a sleeve 18 which loosely surrounds the lower end of cylinder 7 in an enlarged bore of casing 5. Gear teeth 19 are provided on the upper end of sleeve 18 for cooperation with a rack 20 which is slidably mounted in casing 5 for movement transversely thereof.

The lower end of sleeve 18 is axially slotted, as at 22, for slidably receiving the ends of a cross-bar 23 which is rigidly secured to or integral with plunger 13. Sleeve 18 is held against axial movement relative to cylinder 7 by an internal shoulder or flange 21 which engages the lower end of said cylinder and an external shoulder 21' which rests upon the upper surface of an inwardly extending flange on a ring 24. Said ring is posi-

tioned against an internal shoulder in casing 5 and is held in place by any suitable means, such as a snap ring 25. It will be seen, therefore, that upon reciprocation of rack 20, sleeve 18 will be moved angularly in a direction depending upon the direction of movement of the rack and plunger 13 will be correspondingly angularly adjusted through the connection 22, 23 with sleeve 18. Angular adjustment of plunger 13 may thus be effected without hindering the longitudinal or pumping movement thereof.

Suitable means are also provided for reciprocating piston 13 in cylinder 7 in such a manner that the piston will not be subjected to any appreciable lateral force or pressure which would cause any unnecessary friction or binding. In the form shown, said piston operating means includes a tappet cup 26 which is slidably positioned in the lower end of casing 5 for engagement with an enlarged head portion 27 at the lower end of piston 13. Said piston may be moved upwardly by means of a rotating cam, not shown, which operatively engages, either directly or indirectly, the closed end of tappet cup 26 in a manner well understood in the art. The return or downward movement of piston 13 which constitutes the suction stroke may be effected by a coil spring 28 which is interposed between the flange or ring 24 and a slotted washer 29 which engages the upper shoulder of head 27.

Pressure chamber 17 of the pump may be connected by any suitable means to an injection nozzle (not shown) in the cylinder of an internal combustion engine. Although there are many suitable structures known to the prior art, the means shown in the drawings for the above purpose comprises an adaptor element 30 which constitutes a guide and seat for a delivery valve 31. Adaptor 30 rests upon the upper end of cylinder 7 and is held in fluid-tight engagement therewith by a combined nipple and sleeve nut 32 which engages internal threads in the upper end of casing 5. If desired, a packing washer may be interposed between the inner end of member 32 and an external flange 33 on adaptor 30 to further insure fluid tightness. The upper end of member 32 terminates in a threaded portion or nipple 34 having a passage 35 therein whereby a delivery conduit (not shown) leading to the fuel injection nozzle may be attached for communication with the interior of member 32.

Valve guide or adaptor 30 has an axial passage therein through which the flow of fuel from pressure chamber 17 into the interior of member 32 is controlled by delivery valve 31 which has a hollow stem and a tapered head portion adapted to engage a valve seat. A seat for valve 31 is provided in the adaptor and the upper end of the valve stem has a close sliding fit in the adaptor bore. The hollow center of the valve stem is open at the top, as viewed in the drawings, and is in constant communication with the interior of member 32 while the lower end of the bore in the valve is in constant communication with the interior of adaptor 30 through a plurality of radial passages 36. Valve 31 is normally yieldably held in closed position by suitable resilient means, such as a coil spring 37, which is centered by tubular member 38 mounted in nipple 32 and having communication with passage 35.

Fuel or other liquid to be pumped may be supplied to pressure chamber 17 from a supply line 40 (Fig. 2) which enters casing 5 through a port 41. The liquid within supply line 40 is prefer-

ably but not necessarily under slight pressure. The interior of casing 5 has two channel-shaped grooves 42 and 43 that communicate with supply port 40 and substantially surround cylinder 7 so as to communicate with inlet and by-pass ports 11 and 12, respectively. If desired, the grooves or channels 42 and 43 may be formed in a hard metal insert which may be cast or otherwise suitably installed in a groove within casing 5 in a manner now known to the art.

In order that plunger 13 may reciprocate freely in cylinder 7, it is necessary to provide a working clearance around the plunger. In pumps, such as fuel injection pumps, wherein very high pressures are attained in pressure chamber 17 during the pressure or pumping stroke of the plunger, fuel or other liquid from said chamber enters the clearance space between the walls of the plunger and the cylinder. A small amount of leakage or flow in this manner is desirable, particularly in fuel injection pumps, to provide proper lubrication for the plunger but, in prior pumps, such leakage has been excessive and wasteful and the means provided for reducing such leakage in prior pumps have been relatively complicated and inefficient. Novel simplified means are accordingly provided for returning the major portion of the fuel which leaks from chamber 17 to the supply line or other region of low pressure free of any contamination, said means also being adapted to reduce such leakage to a minimum.

In the form shown, the novel means referred to above comprises an annular groove 44 in the surface of plunger 13 and a relatively small diagonal port or passage 45 in the wall of cylinder 7, the outer end of said port being in communication with by-pass channel 43, which in turn communicates with supply line 40, 41. The inner end of port 45 is located approximately 90 degrees from ports 11 and 12 and is adapted to communicate with leakage return groove 44 only when plunger 13 approaches or reaches the top of its pumping stroke, as illustrated in Fig. 3. The circumferential and axial location of port 45 is determined primarily by metering groove 16 in the plunger, which groove also determines the uppermost position of leakage groove 44. The upper edge 46 of groove 44 must be a sufficient axial distance from the lower end of metering groove 16 to prevent excessive leakage of fuel from the latter into groove 44. A safe distance between these grooves differs in pumps of different size and in pumps of the same size if the clearance spaces between the walls of the plunger and cylinder differ in any appreciable degree. It has been found satisfactory to separate the nearest edges of grooves 16 and 44 a distance of about $\frac{1}{8}$ inch in pumps having $\frac{1}{2}$ inch and $\frac{3}{4}$ inch diameter plungers. In larger size pumps, a distance of $\frac{1}{4}$ inch has proved satisfactory. A satisfactory minimum distance in any given pump may be readily determined by test and if other factors permit, a greater distance between grooves 16 and 45 is desirable in all cases. The same considerations apply to groove 16a if such a groove is used.

The inner end of port 45 must, of course, be axially positioned for communication with groove 44 at or near the end of the pressure stroke of the plunger and angularly positioned so that it will be an appreciable distance from grooves 16 and 16a at all times during the "effective" pumping stroke of plunger 13 for all angular adjustments of the plunger from full speed to idling.

When the plunger is in its full load position and is just beginning its effective pumping stroke, i. e., just closing inlet port 11, there should be at least a distance of approximately $\frac{1}{16}$ inch in the above-mentioned smaller size pumps between port 45 and the nearest edge of groove 16. In larger pumps this distance should be correspondingly increased.

The volume of leakage return groove 44 and, hence, the width and depth thereof are important factors in the proper operation of the present pump. The volume of the groove should be sufficiently large so that the compression of the fuel or other liquid which takes place therein will absorb substantially all the fuel which leaks along the wall of the cylinder during each stroke of the plunger. The pressure in the clearance space around the plunger is thus maintained sufficiently high above groove 44 to prevent excessive leakage of fuel. At or near the end of each pressure stroke of the plunger, groove 44 communicates with port 45 and the compressed fuel within the groove expands into channel 43 and, hence, into the supply line. In pumps with plungers having diameters of $\frac{1}{2}$ inch to $\frac{3}{4}$ inch, a leakage groove which is $\frac{1}{16}$ inch wide and .015 to .020 inch deep has proved satisfactory. In pumps of greater size, the volume should be correspondingly increased. In a pump having a plunger diameter greater than $\frac{3}{4}$ inch, for example, groove 44 should be about $\frac{1}{4}$ inch wide and the same depth as recited above. If a lapped plunger is used, care should be taken not to round off the corners of the grooves in plunger 13, particularly the edges of grooves 16 and 16a which are nearest groove 44, during the lapping process.

The relationship of parts and the grooves and ports therein is best illustrated in Fig. 4, which shows the superposed developed circumferences of the pump plunger and cylinder, the plunger being shown in full load position with respect to the cylinder and just closing the intake port 11 on its upward stroke, i. e., at the beginning of its "effective" pumping stroke for full load operation. As will be clear from the description of the operation which follows, metering groove 16 moves to the right relative to port 45 when the plunger is adjusted from full load position toward idling position so that said groove and port will never overlap during an effective pumping stroke of the plunger. This avoids any undue leakage or by-passing of the fuel from chamber 17 directly through port 45.

The pressure in the clearance space around the plunger below groove 44 is relieved or reduced by the presence of said groove but some fuel is permitted to flow past said groove in order to provide satisfactory lubrication for the plunger. If desired, one or more grooves 47 may be provided in plunger 13 below groove 44 so that fuel leaking past groove 44 may accumulate therein, and thus further assure proper and uniform lubrication around the lower portion of the plunger.

In the operation of the above described pump, plunger 13 is reciprocated by suitable cam means acting against cup 26 and spring 28 in a manner well known in the art and heretofore briefly described. On the upward movement of the plunger after it has closed intake port 11, pressure is built up in pressure chamber 17 to a sufficient value to lift valve 31 off its seat, thereby connecting the pressure chamber with the interior of adaptor 31 and nipple 32. Continued upward movement of the plunger forces fuel past the tapered head of valve 31 through ports 36 in the walls of the valve,

the hollow valve stem and tubular member 38, and then through passage 35 to the injection nozzle. The pressure required to pump the fuel through the injection nozzle into the compression chamber of an engine cylinder must in most instances be very substantial. When the desired quantity of fuel has been injected into the engine cylinder, as determined by the angular setting of piston 13, metering groove 16 moves into overlapping relation with cut-off or by-pass port 12, thereby permitting a free discharge of fuel from chamber 17 through passages 14 and 15 into the supply line. This relieves the pressure in the pressure chamber 17 and permits spring 37 to move delivery valve 31 to closed position.

It will thus be seen that during the "effective" pumping stroke of plunger 13, i. e., that portion of the upward movement of the plunger from the time it closes port 11 until helical groove 16 overlaps by-pass port 12, the fuel within pressure chamber 17 is under very high pressure. Because of this pressure, there is a tendency for the fuel to leak along the clearance space between the outer surface of the pump plunger and the inner surface of the pump cylinder. Since the pressure within groove 44 is relatively small during the initial upward movement of the pump plunger, the high pressure fuel which leaks into it is effective to compress the fuel already within the groove at the lower pressure. As pointed out above, the volume of groove 44 is made sufficiently large so that the compression which takes place in normal operation is sufficient to make room for substantially all the fuel which leaks into groove 44 from the compression chamber during each stroke of the plunger. When the plunger nears the end of its upward or pressure stroke, the pressure in groove 44 is relieved through port 45. This cycle is repeated during each stroke of the plunger.

To vary the effective pumping stroke and, hence, the quantity of fuel pumped to the engine cylinder during each stroke of plunger 13, rack 20 is moved to the right or left, as viewed in the drawings, to thereby angularly adjust sleeve 18 and, hence, plunger 13. It will be clear that angular movement of the plunger changes the point in the upward or pressure stroke thereof at which helical groove 16 begins to overlap by-pass port 12 and accordingly varies the effective pumping stroke of the plunger. For idling, piston 13 is turned sufficiently by rack 20 to carry groove 16 to the right relative to ports 11 and 12, as viewed in Fig. 4, to a position in which the groove will register with port 12 during substantially the full upward movement of the plunger after the latter closes inlet port 11.

Although only a single embodiment of the invention has been illustrated in the accompanying drawings and described in the foregoing specification, it is to be expressly understood that the invention may be incorporated in other types of pumps. For example, the invention might be readily incorporated in a pump having a single port for controlling both the by-pass and inlet of fuel or other liquid. Various other changes might also be made, particularly in the design and arrangement of parts illustrated without departing from the spirit and scope of the invention, as will now be readily apparent to those skilled in the art. For a definition of the limits of the invention reference is had primarily to the appended claims.

What is claimed is:

1. In apparatus of the class described, means forming a pressure chamber comprising a cylin-

der and a reciprocating plunger therein, said cylinder having port means therein communicating with a source of supply and through which flow to and from said chamber is controlled by said plunger, said plunger having means thereon including a helical groove in the surface thereof for connecting said port means to said pressure chamber for terminating the effective pumping stroke of said plunger, an annular groove in the surface of said plunger immediately below the lower end of said helical groove and a port in said cylinder adapted to communicate continuously at its outer end with a region of low pressure outside said cylinder and to communicate at its inner end with said annular groove only when said plunger is near the end of its pumping stroke.

2. In apparatus of the class described, means forming a pressure chamber comprising a cylinder and a reciprocating plunger therein, said cylinder having port means in the wall thereof communicating with a source of supply, said plunger having means thereon including a first groove in the surface thereof for controlling the flow to and from said pressure chamber, a second groove in the surface of said plunger spaced below the lower end of said first groove and a port in said cylinder for connecting said second groove with a region of low pressure outside the cylinder only when said plunger is near the end of its pressure stroke, said port being so located that it will not overlap said first groove during the effective pumping stroke of said plunger.

3. In a pump, means forming a pressure chamber including a cylinder having an inlet port and a by-pass port therein, and a piston reciprocable in said cylinder for controlling flow through said inlet port and having passage means for connecting said pressure chamber and said by-pass port at a predetermined point in the pressure stroke of the piston, a groove in said piston having communication with said pressure chamber only through the clearance space around said piston during at least the major portion of the effective pumping stroke of the latter and a port in said cylinder for connecting said groove to a region of low pressure when said piston approaches the end of the pressure stroke thereof.

4. In a pump, means forming a pressure chamber including a cylinder having port means therein and a piston reciprocable in said cylinder for controlling flow to and from said cylinder through said port means, a groove in said piston adapted to communicate with said pressure chamber only through the clearance space around said piston during at least the major portion of the effective pumping stroke of the latter, and a port in said cylinder for connecting said groove to a region of low pressure outside the cylinder when said piston approaches the end of the pressure stroke thereof, the inner end of said port being below 60 said port means.

5. In a piston and cylinder pump of the type wherein the cylinder has inlet and by-pass port means controlled by said piston for determining the effective pumping stroke of the latter, an annular groove in the surface of said plunger, and a port in said cylinder for connecting said groove to a region of low pressure outside said cylinder when the plunger approaches the end of its pressure stroke.

6. In a pump for pumping liquids, or the like, means forming a pressure chamber including a

cylinder and a piston reciprocable therein, an annular groove in said piston having communication with said chamber only through the clearance space between the walls of said cylinder and piston, and port means in said cylinder for connecting said groove to a region of low pressure outside said cylinder whenever said piston approaches the end of the pressure stroke thereof.

7. In a pump of the class described, wherein a piston having a metering groove cooperates with port means in a cylinder for controlling flow to and from the pressure chamber, a pressure relief groove in said piston below said metering groove, and a port in the wall of said cylinder adapted to communicate with said pressure relief groove when the piston approaches the end of its pressure stroke, said port being positioned to remain out of communication with said metering groove during substantially the entire effective pumping stroke of said piston.

8. In pumping apparatus, means forming a pressure chamber including a cylinder and a piston reciprocable therein, said piston having a groove in the surface thereof and said cylinder having a port therein adapted to communicate with said groove only when the piston approaches the end of its pressure stroke, said groove being in communication with said pressure chamber only through the clearance space between the piston and cylinder walls.

9. In pumping apparatus of the class described, a casing, means in said casing forming a pressure chamber including a cylinder and a piston reciprocable therein, a space in said casing around said cylinder in communication with a source of supply, port means in the wall of said cylinder connecting said space and chamber, said port means being controlled by said piston, a port in the wall of said cylinder connecting said space with the interior of said cylinder below said port means at a point which communicates with the pressure chamber only through the clearance space between the piston and cylinder, and a groove in said piston adapted to communicate with said port only when the piston approaches the end of its pressure stroke.

10. In pumping apparatus of the class described, means forming a pressure chamber including a cylinder having inlet and by-pass port means and a port, the inner end of which is spaced below and approximately 90 degrees circumferentially from said port means, and a piston reciprocable in said cylinder adapted to control flow to and from said cylinder through said port means, said piston having a groove in the surface thereof adapted to communicate with said port whenever the piston approaches the end of its pressure stroke.
